UNITED STATES PATENT OFFICE.

GEORGE O. SLINGERLAND, OF MECHANICSVILLE, NEW YORK.

GLOVE BOX.

Application filed February 16, 1922. Serial No. 537,135.

To all whom it may concern:

Be it known that I, GEORGE O. SLINGERLAND, a citizen of the United States, residing at Mechanicsville, in the county of Saratoga and State of New York, have invented certain new and useful Improvements in Glove Boxes, of which the following is a full, clear, and exact description.

My invention relates to boxes for shipping gloves and similar articles, and has for its object to provide a box which is of low cost in manufacture and yet is strong and neat in appearance.

The box is preferably, though not necessarily, made partly of wood and partly of paper and has the various walls so formed as to snugly fit the articles to be packed.

Another object of the invention is the provision of a partition which is held in the box partly through the resiliency of the partition itself.

Other objects and advantages of the invention will be apparent from the following description when taken in connection with the accompanying drawings, in which,

Figure 1 is a perspective view of the complete box.

Figure 2 is a section taken on the line 2—2 of Figure 1.

Figure 3 is a fragmentary section taken on line 3—3 of Figure 1.

Figure 4 is a fragmentary section taken on line 4—4 of Figure 1.

Figure 5 is a perspective view of the central partition of the box, showing the box dotted in outline.

Figure 6 is a plan view of the blank from which the central partition is formed.

Figure 7 is a horizontal section through an end portion of the box, showing the expanded position of the partition in dotted lines, and,

Figure 8 is a vertical section taken on line 8—8 of Figure 2.

Referring to the drawing more in detail, the numeral 1 designates the body of the box formed of pasteboard or the like. To the inner side of each side wall of the box is pasted or otherwise secured a fly leaf 2, and against the lower portion of each fly leaf is secured a strip of wood or the like 3. The strips 3 are tapered at the ends as indicated by the numeral 4 and have their exposed faces covered with paper strips 5. By securing the strips 3 against the fly leaf 2 as shown, they not only reinforce and properly

shape the box but also cover the lower part of the fly leaf and prevent the same from becoming partly detached and interfering with the withdrawal of the gloves or other goods being removed.

The box is divided longitudinally into two compartments by means of the partition 6 which is composed of the two side walls 7 and 8 and integral top wall 9. Each end of each of the side walls 7 and 8 is provided with an extension or tongue 10 which is adapted to be bent at right angles in order that the same may engage the end walls of the box as clearly shown in Figure 5. It is desirable to have the central partition tapered to co-operate with the taper on the side strips 3 and to this end the top wall 9 of the partition is made of substantially less length than the length of the box and is provided with the tapered projections 11. The tongues 10 are each of a length equal to substantially one-half the width of the box, and since the side walls of the partition are spaced a distance equal to the width of the top portion 9 it is obvious that the end portions of the side walls 7 and 8 will taper in the manner shown when the partition is placed in the box. In this connection attention is called particularly to Figure 7 of the drawing, wherein is shown in dotted lines the normal position of the partition before being contracted and placed in the box body.

As clearly shown in Figure 7, the ends of the tongues 10 are clamped between the end walls of the box and the ends of the strips 3. While this construction, due to the resiliency of the side walls of the partition, will tend to hold the partition in place, it is usually found advisable to secure the tongues 10 to the end walls of the box by glue or other well known fastening means. After being positioned in the box as described, the partition may be covered with a facing strip as indicated by the numeral 12.

From the foregoing description it will be seen that I have provided a box which is extremely neat in appearance, is strong and durable, is shaped to fit the articles packed, and is of low cost both in the manufacture of the parts and the assembling of the box.

In accordance with the patent statutes I have described what I now believe to be the best embodiment of the invention, but I do not wish to be understood thereby as limiting myself or the scope of the invention, as many changes and modifications may be

made without departing from the spirit of the invention, all such I aim to include in the scope of the appended claims.

What I claim as new and desire to secure by Letters Patent is:

- 5 1. A substantially rectangular pasteboard box, rigid reinforcing strips secured to the sides of said box and extending the full length of the box, each reinforcing strip being provided with a tapered end.
- 10 2. A box including a hollow central partition engaging the ends of the box, and solid reinforcing strips attached to the side walls of the box, said central partition and reinforcing strips having their end portions tapered.
- 15 3. In a box, a hollow longitudinal partition, and normally spaced tongues extending in opposite directions from said partition adjacent the ends thereof, the total length of each pair of tongues being substantially equal to the width of the box, whereby the bases of adjacent tongues are caused to abut.
- 20 4. In a box, a longitudinal partition comprising a top wall and two spaced side walls, and tongues on each end of the side walls, the total length of each pair of tongues being substantially equal to the width of the box, whereby the bases of adjacent tongues are caused to abut.
- 25 5. In a box, a hollow longitudinal partition comprising a top wall and two spaced side walls, tongues on each end of the side walls, the total length of each pair of tongues being substantially equal to the width of the box, whereby the bases of adjacent tongues are caused to abut, and a facing strip covering the upper portion of said partition.
- 30 6. A blank for partitions, comprising a central section and integral side sections, the central section being shorter than the side sections, the side sections being spaced by the central section, and a tongue formed on each end of both side sections, whereby the ends of the side sections may be bent toward each other.

5. In a box, a hollow longitudinal partition comprising a top wall and two spaced side walls, tongues on each end of the side walls, the total length of each pair of tongues being substantially equal to the width of the box, whereby the bases of adjacent tongues are caused to abut, and a facing strip covering the upper portion of said partition.

6. A blank for partitions, comprising a central section and integral side sections, the central section being shorter than the side sections, the side sections being spaced by the central section, and a tongue formed on each end of both side sections, whereby the ends of the side sections may be bent toward each other.

7. A blank for partitions, comprising a central section and integral side sections, the side sections being spaced by the central section, a projection extending from each end of the central section, and a tongue formed on each end of both side sections.

8. A blank for partitions, comprising a central section and integral side sections, tongues formed on the ends of said side sections, and projections formed on the ends of said central section, the total length of the central section and projections being less than the length of a side section.

GEORGE O. SLINGERLAND.
